ROBERT W. SCOTT, OF BOSTON, MASSACHUSETTS, ASSIGNOR TO SCOTT & WILLIAMS,
INCORPORATED, OF CAMDEN, NEW JERSEY, A CORPORATION OF NEW JERSEY.

METHOD OF KNITTING RIBBED-FABRIC SECTIONS.

1,192,799.

Specification of Letters Patent. Patented July 25, 1916.

Original application filed December 21, 1911, Serial No. 667,224. Divided and this application filed July 23, 1914. Serial No. 852,606.

To all whom it may concern:

Be it known that I, ROBERT W. SCOTT, a citizen of the United States, and resident of Boston, in the county of Suffolk and State 5 of Massachusetts, have invented certain new and useful Improvements in Methods of Knitting Ribbed-Fabric Sections, of which the following is a specification.

The object of my invention is to improve 10 the making of sections of ribbed fabric forming parts of articles partly ribbed and partly plain. Heretofore in the manufacture of such parts, such as ribbed tops for half hose or the ribbed portion of footed ribbed hose, 15 it has always been the practice to knit a tube or flat blank of continuous lengths with welt portions and slack courses formed at suitable intervals, the fabric then being separated into lengths by severing it close to the 20 welt and between the welt and the slack course portion. Usually a space of about one-half inch intervenes between the slack course and the welt, which portion, after the fabric is severed, is used by the operator to 25 facilitate the placing of the stitches upon the needles of the footing machine or upon the impaling points of a transfer ring. These surplus courses are then raveled away, but when the fabric is severed as described, 30 the raw edge left is difficult to ravel and loss of time results.

The practice of my new method comprises the formation of a free raveling edge for each piece, each piece being pressed or cast 35 off separately from the needles of the machine, so that the loops of a terminal course of the superfluous or waste fabric beyond the loose course are free loops, and raveling will start upon pulling the exposed end of 40 the yarn of the last course.

When the ordinary practice is followed, as above described, the welted or finished end of the ribbed fabric is left with each terminal stitch or loop carrying short pieces of 45 yarn, presenting a ragged and unfinished appearance at the juncture of the welt and the body of the piece. Moreover, it is impossible to sever the fabric near the welt in one and the same course, so that leaving part of the 50 previous fabric attached to the welt can not be avoided by mere skill.

One object of my invention is to avoid this defect in the product.

In my copending application, filed De-

cember 21, 1911, Serial Number 667,224 55 (Letters Patent No. 1,114,539 dated October 20, 1914) of which this application is a division, I have described a rib knitting machine provided with web-holding members for acting upon the fabric, in order to enable the 60 machine to be employed for the manufacture of discontinuous sections of fabric. The method or art about to be described may conveniently be practised with the aid of a machine such as that described and claimed 65 in my said parent application.

In the accompanying drawings, Figure 1 is a diagram elevation of a fabric section which is a typical product of my process; Fig. 2 is a diagram diametrical section of a 70 knitting machine such as that disclosed in my said application, illustrating the arrangement of the yarn with respect to the instruments of the machine at the initial course; Fig. 3 is a similar view illustrating 75 the fabric and the machine instruments during the formation of the welt; Fig. 4 is a similar view illustrating the fabric at the moment of being cast from the machine instruments at the end of the section; Fig. 5 is 80 a diagram section of the fabric of Fig. 1.

The article of manufacture produced typically comprises a fast end finish made as a turned welt or hem W which may be very short to constitute a mere selvage, of intermediate length, or comparatively long, as shown for instance in Figs. 1 and 5. Such a welt will comprise an extent of plain fabric knit upon the needles of one carrier of the machine, integrally united at both ends to 90 a body of ribbed fabric of any order of rib R which section R comprises intermediate of its ends and usually near the end opposite to the welt a loose course C followed by a terminal section of waste fabric d. Such a 95 product constitutes the article of commerce known as a ribbed top, or ribbed leg, depending upon the length of the section R and its intended use.

The entire fabric may be raveled in the 100 direction of the arrow r of Fig. 1 by removing in an order opposite to that in which they were formed, each loop of the terminal course of the section d, and each loop of each preceding course.

In normal use the course C is impaled loop by loop upon the points of a transfer implement, or the needles of a second machine, and

the section *d* is then raveled by pulling on the yarn of the terminal course until the course *C* is reached, which will not ravel because of the presence in its loops of said instruments. In the case of imperfect fabric it is a common practice to recover all the yarn by raveling in the manner indicated the entire ribbed top and winding the resulting yarn for re-use.

10 It will be understood from the above that the article of manufacture comprising a ribbed section *R* having a welt *W* at one end, a loose course *C* near the other end, a section *d* beyond the loose course, and a free terminal course, is produced by the prior art steps of manufacture by removing by hand such irregular and severed loops as may occur at the terminal end of the section *d*, and may be produced by hand with respect to the 20 welt *W* by removing therefrom all parts of the previous course connected thereto, although I am not aware of any hand manufacture finished to this extent.

25 In order to produce as a machine manufacture a ribbed top finished in the above particulars, I proceed as follows: I have selected for illustrative purposes in order to explain the steps of my method a machine of the stationary needle-cylinder type comprising a bed-plate 1, a drive-ring 2, carrying a cam-ring 3 for the actuation of the cylinder needles *x*, which are carried in a cylinder or carrier 5 concentric with a relatively stationary needle dial 7, in radial 30 grooves of which the dial needles *y* are placed for actuation by the cam-cap 8. Assuming the needles *x* and *y* to be empty of previous yarns, as shown in Fig. 4, I proceed to form the first or setting-up course *w* for the welt by opening the latches of both sets of needles by any usual implement, and advancing them to take a yarn now supplied to them in common, the said yarn extending from the hook of a cylinder needle to the hook 40 of a dial needle, then to the hook of a cylinder needle, and so on. By preference, at this point the draft given the cylinder needles *x* is less than that used for rib knitting, so that the setting-up course *w* will be 45 of about the same length of loop as a normal knit course. After one or more revolutions when each needle has at least one loop or bight of yarn in its hook, the dial needles *y* are drawn downward to the position illustrated in Fig. 2, which position they retain during the knitting of the fabric for the welt *W* upon the cylinder needles *x* only. 50 In order to enable this operation the machine illustrated is equipped with web-holders 6, such as those described and claimed in my said application, having beveled surfaces 31, and a downward pointing horn 16, in such relation to the cylinder needles as to cause the bight of yarn lying 55 between two cylinder needles to be thrown

inwardly by the surface 31 to take beneath the horn 16 upon the upward movement of the web-holders 6 and to be retained beneath the horn 16 during the advance of the cylinder needles *x* to clear its latch to take 70 a new loop. Several courses (depending upon the number required in the welt) are now formed in this manner upon the cylinder needles only, the dial needles are then returned to active position, that is to say, so 75 that their hooked ends receive the yarn from the cylinder needles, and normal operation of the machine proceeds to produce ordinary ribbed fabric.

80 It has heretofore been thought necessary to maintain a longitudinal stress upon the fabric throughout the operation, which longitudinal stress necessitated a continuous length of fabric long enough to reach a web take-up device of some form. As I have explained in my said parent application, I have, in order to provide one form of instrument for practising the steps of the method herein described, avoided the necessity of maintaining a continuous longitudinal strain by utilizing the behavior of the surface of the parts 31 and 16, of the web-holders 6, to maintain the stress of the yarn with respect to the hooks of the cylinder needles and the dial needles, and thus to 85 avoid strain transmitted through the previously formed fabric. The said web-holders 6 are raised at a point somewhat in advance of the rising phase of the movement given the cylinder needles *x* thus causing the horn 16 on each web-holder to be forced past the yarn carried in the hooks of the dial needles, so that said horn is brought above the yarn, then slightly lowered so that the lower face of the horn 16 is partly in 90 contact with the yarn and then held in this position during the operation of the cylinder and dial needles to clear their loops back of their latches and receive new yarn for a new course of rib fabric from the yarn carrier. The cylinder needles are first retracted to place a bight of the new yarn within the hooks of the dial needles, and at the same time the old loop on the cylinder needle is 95 knocked over the new yarn in the hook of 100 said cylinder needle. The dial needle is now correspondingly retracted so that the old loop upon it is brought into position for being cast over the new yarn in its hook, and at this juncture the web-holders are depressed to act upon the old loop on each 105 side of the dial needle to effectually cast it 110 over the new loop. At the next revolution of the machine the loop previously acted upon by the web-holders has become a 115 sinker wale of the ribbed fabric, and at each revolution these sinker wales are so acted upon by the horns of the web-holders that 120 strain is applied to the loops of the course preceding that which is being drawn by the 125 130

dial needles, to effect the knocking of the stitches of said preceding course over the new yarn in the hooks of the dial needles.

The operation of the web-holders 6 and 5 the needles *x* during production of the welt fabric will be readily understood from an inspection of Fig. 3, the rising movement of the web-holders serving to pass the horn 16 over the yarn extending between two adjacent cylinder needles *x* to prevent the loops of the cylinder needles following said cylinder needles when they are subsequently advanced to clear their latches. Having formed the setting-up course as described, 10 having then knit a sufficient extent of welt fabric, and having thereafter knit a sufficient amount of fabric to form the ribbed top or ribbed leg, the needles of one or both carriers are operated to form the loose 15 course C in the well known manner, which may comprise giving the needles in one or both carriers an extra draft, or separating the carriers themselves, or lifting one or both sets of needles from their grooves; and 20 the machine is thereafter operated to make rib fabric similar to that for the section R for the waste section *d*. The fabric is now cast from the needles, for instance by projecting and retracting the needles at a point 25 remote from the yarn guide, in order to clear the latches of both sets and retract the needles empty, producing the condition illustrated in Fig. 4. The finished product now drops by gravity from the machine as illustrated in said figure. The yarn *m* will now 30 extend from the last loop knit to the yarn guide. While I may include severing the yarn at the stage in the operation indicated by Fig. 4, I prefer to leave the sections connected by the easily broken yarn *m*. The 35 yarn or yarns connecting adjacent sections may be broken, cut or otherwise severed as a manual operation, enough of the yarn *m* being left attached to each section to be picked up and pulled by hand by the operator. The 40 remaining steps comprise impaling the loops of the course C on the transfer implement or the needles of another machine, and thereafter pulling upon the yarn *m* to destroy the section *d*, and thereafter knitting 45 the remainder of the article.

While I have illustrated a circular machine it will be obvious that my method is independent of any particular machine, and 50 equally applicable to flat-blank ribbed tops of legs having welt, loose course, and ravel sections, in which case the instrument of manufacture may be a straight machine. The procedure ordinarily will include again 55 introducing the yarn to the needles as above described to form a new setting-up course *m* and thereafter repeating all of the operations in the same order, to form a succession of tops or legs disconnected except by the 60 run of yarn *m*.

What I claim is:

1. The art of knitting sections of ribbed fabric comprising first forming on a suitable series of instruments free of previous fabric a plain fabric welt, then knitting in continuation thereof an extent of ribbed fabric and then casting off the completed section, whereby said end-finish is free from parts of previous fabrics and said section terminates in a free raveling course. 75

2. The art of knitting sections of ribbed fabric for use in articles to be completed by another knitting operation comprising first forming upon suitable series of instruments free of previous fabric a turned welt constituting a fast end-finish, then knitting an extent of fabric in continuation thereof, and then casting off of said instruments the terminal course of the completed section whereby said section ends in a course of loops free to be raveled back to a course to be engaged by fabric begun thereat. 80

3. The art of knitting fabrics comprising the following steps: first forming a welt, thereafter knitting in continuation of said welt ribbed fabric, and thereafter casting off from the instrument or instruments of manufacture the last knit course, and thereafter repeating said operations whereby to form a plurality of separate sections of ribbed fabric each comprising a welt at one end and a free raveling course at the other end, said sections being connected by a run or runs of unknit yarn. 85

4. The art of knitting fabrics comprising 100 the following steps: first forming a welt, thereafter knitting in continuation of said welt ribbed fabric, and thereafter casting off from the instrument or instruments of manufacture the last knit course whereby a section of ribbed fabric comprising a welt at one end and a free raveling course at the other end is formed, and thereafter knitting an article having an initial course engaged with a course of said section between its ends and raveling the fabric between said last knit course and said intermediate course. 105

5. The art of knitting fabric comprising first knitting a fast end finish, then knitting 115 ribbed fabric, and then casting off of the instrument or instruments of manufacture the last knit or terminal course, whereby a section of ribbed fabric characterized by a fast end-finish at one end and a free raveling course at the other end is formed, and thereafter knitting fabric in continuation of a course intermediate of said ribbed section, said last-mentioned operation including raveling that portion of said ribbed section 120 between said terminal course and said intermediate course. 125

6. The art of knitting sections of ribbed fabric having an end-finish at one end and a waste section at the other end, comprising 130

first forming a setting-up course upon a series of instruments bare of previous fabric, for a first section, thereafter forming fabric for a welt or selvage, thereafter knitting ribbed fabric while maintaining tension upon the yarn of courses previous to the course being knit, thereafter casting the terminal course from the instruments, and thereafter repeating said operations for another section connected to said first section by a run of yarn, and then severing said run of yarn between said sections.

7. The art of knitting fabrics having transferred previously knit sections comprising the following steps; first knitting with the aid of a suitable series of instruments a section of fabric having a fast end

finish at its beginning edge, then casting from said instruments all the terminal loops of said section, whereby said terminal loops are in condition to ravel; thereafter applying the loops of a course between the beginning and end of said section to another series of instruments, then raveling the terminal part of said fabric as far as said applied loops, and thereafter knitting attached fabric.

In testimony whereof, I have signed my name to this specification in the presence of two subscribing witnesses.

ROBERT W. SCOTT.
